RICHARD R. CARDALL, OF SALT LAKE CITY, UTAH, ASSIGNOR OF ONE-HALF TO
HARRY SHEPHERD, OF SALT LAKE CITY, UTAH.

COMBINED POSTING-BOX AND FILE.

1,356,851.

Specification of Letters Patent. Patented Oct. 26, 1920.

Application filed April 9, 1918. Serial No. 227,558.

To all whom it may concern:

Be it known that I, RICHARD R. CARDALL, a citizen of the United States, and a resident of Salt Lake City, in the county of 5 Salt Lake and the State of Utah, have invented a certain new and useful Combined Posting-Box and File, of which the following, together with the accompanying drawings, forms a full, clear, and exact specification, which will enable others skilled in the art to which it appertains to make and use the same.

This invention relates to a combined posting-box and file designed particularly for 15 use in invoicing and billing in connection with modern systems of mechanical book-keeping and it is adapted for use in many different lines of business.

The principal objects are:

20 1. To produce a combined posting-box and file, which shall have few parts and which shall require few operations on the part of the user.

25 2. Be easily and quickly brought from filing position to posting position and vice versa.

30 3. Be adjustable to convenient positions for reference and for manipulation by the operator when used as a posting-box, thereby facilitating the handling of the papers and making extremely rapid work possible.

35 4. Which shall have a large capacity, thus eliminating the use of at least two and sometimes more, cumbersome "binders."

5. Have its principal working parts adjustable within wide limits, both as to convenience and capacity.

6. Be available when desired, as a file which may be secured under lock and key.

40 7. Be positive in its operation and not liable to get out of order.

8. Securely hold the papers in an upright position when used as a file and allow the papers to be easily accessible for reference.

45 9. Take up a minimum of vault space.

10. Which shall be simple and economical to manufacture.

In attaining the objects specified, an elongated box is preferred, which may be made 50 of wood or metal, the same being provided with hinged covers, a hinged end section and hinged side sections. One of the cover sections may be hinged to the pivoted end section which allows the forming of an angular depending apron, constituting the

front of the box. The side section or sections may be hinged longitudinally in any convenient manner and may be arranged to open out and drop down, making the interior of the box freely accessible to the 60 user. On the inside of the box, a folding rack is provided, which may be carried on small wheels and may be set at a right angle for filing and at various other angles for use in working position, so that a stack of 65 papers may be placed therein and assume an angle across the edge which will facilitate the operator's picking up one sheet at a time. This rack is movable longitudinally along the interior of the box and is so arranged that it may be securely clamped 70 against the side of the box in any position in which it may be desired to hold the same. The features on which protection is desired are collectively grouped in the appended 75 claims.

In the drawings, which illustrate merely one general embodiment of this invention:

Figure 1 represents a longitudinal vertical section, showing the interior working 80 parts in elevation, the entire box being closed and used as a file.

Fig. 2 is similar to Fig. 1, with the exception that the box is shown opened out and the various parts thereof arranged in position ready for posting.

Fig. 3 is a transverse section on line 3—3 in Fig. 1, looking in the direction of the arrows.

Fig. 4 is a transverse section taken on 90 line 4—4 in Fig. 2, looking in the direction of the arrows, the rear portions of the V-shaped rack being omitted.

Fig. 5 is a fragmentary longitudinal section corresponding to Fig. 1, but showing 95 an alternate position of some parts.

Figs. 6, 7, 8 and 9 are enlarged fragmentary views, showing various details.

Fig. 10 is a perspective view of this device opened out in working position and in 100 the process of being used as a posting-box.

Throughout the different views, the same parts are designated by the same reference numerals.

Referring to the drawings, 20 (Figs. 1 to 105 5) represents part of a metal box of suitable dimensions, having the hinged cover sections 21 and 22, the hinged end section 23 and the hinged side section 24; the cover section 22 being hinged directly to the end section 23, 110

as shown in Figs. 1 and 2. The cover section 21 and the side section 24 may be thrown open to the positions shown in Fig. 2, and the end section 23, together with the cover section 22, may be opened out in one operation to the position shown in the same figure. The end section 23 may be supported in the open position, by a small brace 25, pivoted at 26 and having the heel 27 adapted to hold it in position to rest on the stop 52 (Fig. 2). The top section 22 is supported in the open position (Fig. 2) by the joined arm sections or links 28, 29 and 30, the latter being pivoted to the side of the box at 31. At 32 is a tie rod for holding the unsupported portion of the side 24^a, the former at the same time providing a support for the arms 30. On the inside of the box is the folding V-shaped rack, which may be made of wood or metal, and consists of the rear portion or leaf 33 and the front portion or leaf 34. The front portion 34 has slidably disposed thereon, the section 34^a, thus making this part of the rack extensible to the extreme capacity of the box. The leaves 33 and 34 are pivoted to each other by a rod or pin 35 and this rod may have, rotatably mounted thereon, the small wheels 36. The two leaves of the V-shaped rack may be connected to each other by the side bar 37, pivoted to the leaf 33, while its other extremity passes through the guard 38 attached to the leaf 34^a. The side bar 37 may be adjustable in the guard 38 by means of one or more notches 37^a as shown in Fig. 2, which may engage the lower part of the guard. By means of the side bar 37, the leaf 34 may be set, relatively to the leaf 33, at any desired angle for allowing the operator to conveniently pick up the sheets, one at a time, from the stack 39 (Fig. 2).

In order to hold the rack securely in any certain position in the box, a long rod 40 is provided, extending longitudinally along the inside of the box, adjacent to the rack and having its ends turned off eccentrically to the axis of the rod, the eccentric ends being journaled in the bearings 41 and 41^a (Figs. 1 and 2). At its forward end, the eccentric rod 40 has the rigidly mounted lever 42, and a short distance back therefrom, is covered by a shield or curtain 43, preferably made of metal, the purpose of which will presently be made clear. The rack leaf 33 has attached to one side thereof the friction pads 44, made of rubber or other suitable material and the rack portion 34^a has the friction pads 45, all of these friction pads being so arranged that they will bear on the inside surface of the wall 20^a which forms one side of the box. The position of the wall 20^a is indicated by the dash line in Fig. 2, and while this wall is hinged, the normal position of the hinged portion is always as indicated in Figs. 3 and 4, the drop

feature being provided only for use in special cases when papers are to be taken out of the rack from that side, at such times, however, the lower friction pad is sufficient to hold the rack in place.

When the rack is in the free position in the box, the rod 40 with its operating lever 42, is in the position indicated in Fig. 3 and shown enlarged in Fig. 6. When it is desired to lock the rack in any certain position, for instance, that shown in Fig. 2, the lever 42 is brought down into the position indicated in Fig. 4 and shown in enlarged detail in Fig. 7. This action causes the eccentric rod 40 to bear against the shield 43, moving the latter against the rack and causing the rack to be wedged against the side 20^a and to take its bearing on the anti-friction pads 44 and 45, thereby holding the rack securely in position. It will be noticed that the shield 43 serves the purpose of preventing the rod 40 from touching the sides of the rack, directly, as the frictional engagement thereof would cause its further travel to pull down the side of the rack contacted, thus distorting it and making it unfit for use. The lever 42 has the heel 42^a, which limits its downward travel.

When the box is used as a file, the stack of papers being set vertically on edge, as shown in Fig. 1, it is desirable to have an adjustable follower 46, which may be locked in position against the papers, according to the varying quantities thereof contained in the file. The follower 46 may be moved longitudinally along the rack by means of the guides 47 (Figs. 8 and 9), fixed to the bottom of the follower and which slidably engage the guide-plate 48, the latter being fixed to the extensible section 34^a of the rack. The follower 46 has the slot 49 preferably cut in the lower corner thereof, which is adapted to allow the eccentric 50 to extend through the same when the eccentric is brought to the lower or clamping position indicated by the dotted lines 50^a in Fig. 9. The eccentric 50 is pivoted in the bearings 51 and is adapted to clamp the guides 47 tight up against the plate 48. When it is desired to refer to any papers contained in the file, it is only necessary to open the cover sections 21 and 22. When the cover section 22 is thus opened, the folding arms 29 and 30 will be caused to assume the position shown in Fig. 5. The various parts of the box may be securely held in their closed positions by suitably arranged spring catches (not shown) and the cover sections 21 and 22 may be provided with any suitably arranged lock (not shown).

In using this device, its service as a file is self-evident by reference to Fig. 1. In using it as a posting-box, the end section 23, with its hinged cover section 22, is simply opened out in one operation to the position shown in

Fig. 2, without the necessity of making any 65
adjustments, the brace 25 falling out by
gravity to its proper position and automatically
taking its bearing on the stop 52.
5 Next, the eccentric rod, which is assumed
to have been clamped against the movable
rack in the position shown in Fig. 1, is
loosened, the rack is then pulled along on its
wheels and tilted upwardly until the stack
10 of paper will remain in position by gravity,
thereupon the rack is temporarily clamped
in position by means of the eccentric rod,
after which the follower 46 is removed en-
tirely, and the eccentric rod again loosened,
15 the user meanwhile holding the rack with
one hand. Thereupon the rack is adjusted
to the desired place and inclination, being
held by one hand of the user, while with
the other hand the lever 42 is thrown down
20 into the position where the rack is clamped
tightly into place and the posting-box is
ready for use.

The use of the posting-box will be self-
evident by reference to Fig. 10, which shows
25 this device constructed of wood and the
hand of a user in the act of taking the sheets
out of the V-shaped rack for placing in the
billing machine. After the sheets are taken
30 out of the billing machine, they are put into
the depending V-shaped apron formed by
the parts 22 and 23, the arms 28, 29 and 30
forming side guards for the accumulating
stack of papers.

In use, the box may be set on a small
35 stand to the right of the operator and within
in easy reach of the seat at the billing ma-
chine.

In order to prevent the file from tipping
over, as the weight in the apron increases,
40 a clip 53, (Figs. 2 and 10) is provided,
which may project through a small opening
in the back of the box as shown, thereby
holding down the rear end of the box.

While a satisfactory embodiment of this
45 invention is herein described and illustrated,
the details thereof are not necessarily in the
preferred form.

What I claim is:

1. In a combined posting-box and file,
50 the combination with an open main body
portion, of movable members adapted to
allow the closing of the said body portion,
a part of the said movable members being
55 adapted to form a receptive apron, and
means for supporting the said apron in an
opened-out position.

2. In a combined posting-box and file, the
combination with a main body portion, of a
50 pivoted end section, pivoted side section and
pivoted top sections, adapted to be opened
out for exposing the interior of the said
body portion to convenient access; a suit-
able rack adapted to hold stacked papers,
the said rack being movably disposed in the

said body portion; and means for holding 65
the said rack in fixed positions.

3. In a combined posting-box and file, the
combination with a main body portion, com-
prising an end, a side and a bottom, of a
hinged end section, a hinged side section and
hinged top sections, the said hinged end
70 section and one of the top sections being
adapted, together, to form a V-shaped
apron, and means for supporting the V-
shaped apron.

4. In a combined posting-box and file, the
combination with a main body portion hav-
ing a side section, an end section and top
sections adapted to be opened out for the
purpose of exposing the interior of the said
body portion, the said end section and the
80 said top section being adapted to form a
support for holding a stack of papers; of
a rack movably disposed in the interior of
the said body portion, and means for hold-
ing the said rack fixedly in convenient op-
erating positions.

5. In a combined posting-box and file, the
combination with an open body portion, of
movable sections adapted to form a closure
90 for said body portion, means for adjust-
ably supporting a stack of papers inside
the said body portion and a part of the said
movable sections being adapted for sup-
porting a second stack of papers exteriorly
95 adjacent to the said main body portion.

6. In a combined posting-box and file, the
combination with a main body portion, of
a movable apron depending therefrom
adapted to hold a stack of papers; and
means for adjustably holding a stack of
100 papers inside the said main body portion.

7. In a combined posting-box and file, the
combination with a main body portion, of
a movable apron depending therefrom and
adapted to hold a stack of papers; means for
adjustably holding a stack of papers on the
105 interior of the said body portion, and mem-
bers, which in conjunction with the said
body portion and the said apron, will al-
low the formation of a tightly closed box.
110

8. In a posting-box, the combination with
a main body portion, of a depending apron
adapted to hold a stack of papers, and means
for adjustably holding a stack of papers on
the inside of the said body portion.

9. In a posting-box, the combination with
a main body portion, of a movable apron de-
pending therefrom adapted to hold a stack
120 of papers, and means for holding a stack
of papers on the inside of the said body
portion.

10. In a posting-box, the combination with
a main body portion, of a movable
apron depending therefrom, means for sup-
porting the said apron, a folding rack
125 adapted to hold papers movably disposed
inside the said body portion, and means for

rigidly holding the said rack in any convenient working position.

11. In a posting-box, the combination with a main body portion, of a movable apron depending therefrom, means for supporting the said apron, a folding rack adapted to hold papers, movably disposed inside the said body portion, and a suitably supported rod extending longitudinally along the inside of one wall of the said body portion, the said rod being adapted to move eccentrically in its bearings for the purpose of clamping the rack in suitable positions for convenient access.
12. In a combined posting-box and file, the combination with a main body portion, of a pivoted end section and pivoted top section adapted to form an apron, a movable rack suitably disposed in the said body portion, a movable rod extending along the inside of the said body portion, the said rod being eccentrically mounted in its bearings and adapted for clamping the said rack in any suitable position.
13. In a file, the combination with a box portion, of an adjustable rack, movably disposed inside the said box, and an eccentrically mounted rod for the purpose of clamping the said rack in any suitable position in the said box.

14. In a file, the combination with a movable end section adapted to form an apron for the purpose of holding a stack of paper, of a box having a movable rack suitably disposed therein, and an eccentrically mounted rod adapted to clamp the said rack firmly in any suitable position.

15. In a combined posting-box and file, the combination with a box portion having hinged top, side and end sections, an end section and a top section thereof being adapted to form a depending apron; pivoted arms extending outwardly from the said box portion above the said depending

apron and links for supporting the said 45 apron from the said projecting arms.

16. In a combined posting-box and file, having a main box portion of a V-shaped rack, movable along the interior of the said box portion, friction pads on one edge of 50 the said rack, and means for clamping the said rack in such a manner that the said friction pads will bear tightly against a surface of the said box portion.

17. In a combined posting-box and file, 55 having a main box portion, of a folding V-shaped rack, a pivoted side bar adapted to hold the leaf portions of the V-shaped rack in adjusted relation to each other, the said rack being movable along the interior of the said box portion; friction pads suitably disposed on the said rack for the purpose of bearing against a surface of the said box portion, and an eccentrically mounted rod having a lever, for the purpose of clamping 60 the said rack against the said surface of 65 the box portion.

18. In a combined posting-box and file, the combination with a main body portion, of an adjustable V-shaped rack comprising 70 pivoted leaf portions, the said rack being movably disposed inside the said body portion; an eccentrically mounted rack clamping rod having a lever, movably disposed in the said body portion, and a suitable shield 75 depending over the said eccentric rod in such a manner that the surface of the said rod will not contact directly, the said V-shaped rack.

In testimony that this invention is 80 claimed as my own, I affix my signature 80 hereto in the presence of two subscribing witnesses.

RICHARD R. CARDALL.
